Seating Company, Grand Rapids, Mich., a cor-
poration of New Jersey

Application May 28, 1945, Serial No. 596,380

2 Claims. (Cl. 155—91)

1

The present invention relates to chairs, and more particularly to chairs for occupancy by the operators of motor busses and other vehicles.

The primary objects of the invention are to provide a bus driver's chair which is adjustable to accommodate persons of different physique and to suit the preferences of the individual; to provide such a driver's chair which is adjustable as to height, as to forwardly-rearwardly moved position, and as to the tilt of seat and back; and to provide such a driver's chair which is sturdy in construction, convenient to adjust, and reasonably economical to manufacture.

These objects are attained by the preferred embodiment of the invention shown in the accompanying drawings, wherein:

Figure 1 is a right hand and front perspective view of the chair in its maximum raised position of adjustment;

Figure 2 is a left hand and front perspective view of the chair in its maximum lowered position of adjustment;

Figure 3 is a top plan view of the chair showing the seat in a raised position in order to disclose the chair-supporting parts below the seat;

Figure 4 is a perspective view of a link which forms a part of the chair-supporting pedestal;

Figure 5 is a fragmentary vertical sectional view of the chair taken on line 5—5 of Figure 3, showing the chair seat in side elevation with a portion broken away, and showing the chair in its maximum raised position of adjustment;

Figure 6 is a sectional view similar to Figure 5 and taken on the same line of Figure 3, showing the chair frame and seat in side elevation, and showing the chair in its maximum lowered position of adjustment;

Figure 7 is a fragmentary sectional view taken on line 7—7 of Figure 5;

Figure 8 is a fragmentary sectional view taken on line 8—8 of Figure 6;

Figure 9 is a fragmentary side elevational view showing the chair back frame in a rearwardly tilted position; and

Figure 10 is a fragmentary sectional view taken on line 10—10 of Figure 7.

Referring now in detail to these drawings wherein like parts are designated by the same numerals in the several views, the bus driver's chair therein illustrated generally comprises a chair-supporting pedestal upon which is mounted a seat and back assembly. The pedestal is adjustable as to height, and includes an upwardly tapering base 1 of rearwardly opening U-shaped cross section and provided with flanges 2 for se-

curing the base to the floor of a vehicle by means of bolts 3.

A downwardly tapering seat bracket 4 of forwardly opening U-shaped cross section is connected to the base 1 by a pair of rearwardly extending links 5, 6. The lower link 5 is of upwardly opening U-shaped cross section and has its forward end pivotally mounted on a pintle 7 secured within the base and extending transversely thereof. The rearward end of the lower link 5 is similarly pivotally mounted on a pintle 8 which is secured within the seat bracket 4 and which extends transversely thereof. The side flanges 9 of the lower link 5 have on their upper or forward edges arcuate racks 10 each comprising a series of spurs 11 arranged in an arc concentric with the pivotal connection of the link 5 to the seat bracket 4.

The upper link 6, which is shown per se in Figure 4, is of downwardly opening U-shaped cross section and has its forward end pivotally mounted on a pintle 12 transversely secured in the base 1 above the pintle 7, and has its rearward end similarly pivotally mounted on a pintle 13 transversely secured in the seat bracket 4 above the pintle 8. The upper link's web portion 14 has a pair of slots 15 therethrough whose function will hereinafter be described.

An extension spring 16 has its forward end connected to the pintle 12 on the base 1, and its rearward end connected to a rod 17 secured transversely in the seat bracket 4 between the pintles 8 and 13. The arrangement of the spring 16 is such that the seat bracket 4 and the seat and back assembly are normally urged forwardly and upwardly. This result is achieved by an arrangement of the spring 16 in which the distance between the pintle 13 and the spring's point of attachment to the seat bracket 4, is greater than the distance between the pintle 12 and the spring's point of attachment to the base 1, which latter distance is zero in the arrangement shown. As illustrated in Figure 3, the spring 16 may comprise a pair of individual spring units disposed side by side in order to provide sufficient tension to raise the seat and back assembly, and this tension is such as to yield against the weight of a chair occupant.

A pair of detents 18 is pivotally mounted on a pintle 19 secured transversely in the seat bracket 4, and these detents extend downwardly through the slots 15 in the upper link 6 and into engagement with the spurs 11 of the arcuate racks 10 on the lower link 5. A lever 20 for effecting vertical adjustment is mounted in

a slide bearing member 21 on the left hand end of a strut 22 which connects the detents 18 and extends through an elongated aperture 23 in the left hand side wall of the seat bracket 4 (see Figures 7 and 10). It will be seen that when the forward end of the adjustment lever 20 is moved upwardly as shown in dotted lines in Figure 5, the detents 18 are moved forwardly out of engagement with the arcuate racks 10. A tension spring 24 connected to the strut 22 and to the rear wall of the seat bracket 4 normally urges the detents 18 into engagement with the arcuate racks 10 to thus releasably secure the seat in vertically adjusted position.

A plate 25 is horizontally disposed on top of the seat bracket 4 and is secured as by welding to mounting brackets 26 on the seat bracket. A channel iron 27 and an angle iron 28 secured to the plate 25 by means of bolts 29 and nuts 30, form slide bearings for forwardly-rearwardly extending rods 31, 32 respectively which form a part of the tubular seat frame 33 on which is mounted the seat 34. A horizontal adjustment lever 35 is turnably mounted between angle brackets 36 secured as by welding to the seat bracket 4, and said lever 35 is operably connected to a pin 37 by means of a collar 38 on the pin. A compression spring 39 interposed between the collar 38 and a mounting bracket 40 for the pin 37, normally urges the pin into engagement with one of a series of horizontal apertures 41 in the rod 32 to thus secure the seat frame 33 and the seat 34 in selected forwardly-rearwardly moved position.

The vertical adjustment lever 20 is provided with a pin 42 which extends upwardly through a vertical opening 43 through the rod 32 and has a stop 44 secured on the upper end thereof by means of a cotter 45. A compression spring 46 interposed between the lever 20 and the rod 32 normally urges the lever 20 downwardly, which movement is checked by contact of the stop 44 with the rod 32. An aperture 47 in the seat bottom 48 permits upward travel of the pin 42.

The seat 34 is hingedly secured to the front portion of the seat frame 33 by means of hinge straps 49, 50 which are secured to the seat bottom 48 by screws 51 and which surround the tubular seat frame.

Means are provided whereby the angular tilt of the seat 34 may be varied as desired by the operator of the vehicle, which means comprise a seat-tilt adjustment lever having a handle 52, a bearing 53 turnably mounted on the rear portion of the tubular seat frame 33 and provided with radially extending arms 54, 55, and 56 of different lengths. The seat has a stop plate 57 secured by screws 58 to the seat bottom 48 and provided with lugs 59 adapted to engage one of the arms 54, 55, and 56, and the rear of the seat 34 is thus supported in a selected position of elevation.

The chair back 60 is secured in any conventional manner to a tubular chair back frame 61 which comprises an inverted U-shaped medial portion and downwardly and forwardly extending arms 62, 63 pivotally connected by means of pins 64, 65 to the opposite sides respectively of the seat frame 33. The right hand arm 62 of the chair back frame 61 is extended forwardly, and is provided at its forward end with a depending lug 66 secured thereto as by welding. A back-tilt adjustment lever 67 is pivotally connected at 68 to the lug 66 and has a pin 69 extending through a slot 70 in an adjustment plate 71 secured as by welding to the seat frame 33. A leaf

spring 72 is secured to the underside of the outwardly turned upper portion of the lever 67, and said spring bears against the arm 62 of the chair back frame to normally urge the pin 69 into engagement with one of several notches 73 adjoining the slot 70 in the adjustment plate 71.

It will be seen that when the back-tilt adjustment lever 67 is depressed, the pin 69 is disengaged from the notches 73 and the chair back frame is thus free to turn about its pivotal connections with the seat frame 33. The range of such movement is limited by the length of the slot 70, and the lever 67 may be released at any of several points within said range to thus engage the pin 69 in a notch 73 and secure the chair back in selected, angularly adjusted position.

It will be seen that a vehicle driver's chair has been provided which is adjustable in height and adjustable forwardly-rearwardly to accommodate drivers of different bodily structure thus to facilitate each driver's manipulation of the vehicle's controls, and that the chair back and chair seat are independently angularly adjustable to suit the preference of each driver.

While but one specific embodiment of the invention has been herein shown and described, it will be understood that certain details of construction may be altered or omitted without departing from the spirit of the invention as the same is defined by the following claims.

We claim:

1. In a chair, in combination: a base adapted for installation on the floor of a vehicle or the like, a lower link having a web portion and upwardly extending side flanges pivotally connected to the base, an upper link having a web portion provided with horizontally spaced slots there-through and downwardly extending side flanges pivotally connected to the base above the lower link, said links extending rearwardly and upwardly from said base in vertically spaced substantially parallel relation, a seat bracket pivotally connected to the upper rearward ends of said links on vertically spaced horizontal axes, arcuate racks on the side flanges of the lower links arranged concentrically with said links' pivotal connections to the seat bracket, detents pivotally connected to the upper portion of the seat bracket said detents depending through the slots in the upper link's web portion and being adapted to engage the racks on the lower links in various vertically adjusted positions of the seat bracket, spring means normally urging said detents into engagement with said racks, manually operable means for disengaging said detents from said racks, and a seat mounted on the seat bracket.

2. In a chair, in combination: a base adapted for installation on the floor of a vehicle or the like and comprising an upstanding front wall and spaced upstanding side walls extending rearwardly from said front wall, a pair of horizontal pintles mounted on and between said side walls in vertical alignment, a lower link having a web portion and upwardly extending side flanges pivotally mounted at their forward ends on the lower pintle of said pair, an upper link having a web portion and downwardly extending side flanges pivotally mounted at their forward ends on the upper pintle of said pair, a seat bracket comprising an upstanding rear wall and spaced upstanding side walls extending forwardly from said rear wall, a pair of horizontal pintles mounted on and between said side walls in vertical alignment and having pivotally connected thereto the rearward ends of said upper and lower

links respectively, a spring connected to the base and to the seat bracket for normally urging the seat bracket in an upward direction, arcuate racks on the lower link's side flanges arranged concentrically with said link's pivotal connections to the seat bracket, detents pivotally connected to the seat bracket and adapted to engage said racks in various vertically adjusted positions of said seat bracket, spring means normally urging said detents into engagement with said racks, manually operable means for disengaging said detents from said racks, forwardly-rearwardly extending slide bearings on the seat bracket, a seat frame mounted in said slide bearings for forward-rearward movement therein and a seat on the seat frame movable therewith to forwardly-rearwardly adjusted positions and with the seat bracket to vertically adjusted positions, and manually operable means for releasably securing said seat frame in forwardly-rearwardly adjusted 20 positions.
